CLAIM

I claim the ornamental design of a jewelry display rack, as shown and described.

DESCRIPTION

FIG. 1 is a left front elevational view of the jewelry display rack showing my new design;

FIG. 2 is a front elevational view thereof;

FIG. 3 is a front view thereof;

FIG. 4 is a right elevational view thereof;

FIG. 5 is a right rear view thereof; and,

FIG. 6 is a right rear elevational view thereof.

The broken lines shown in the drawing are for illustrative purposes only and form no part of the claimed design.
